GUARD STRUCTURE

Merle L. Fisher, Canton, Ohio, assignor to James R. Kearney Corporation, St. Louis, Mo., a corporation of Missouri

Application July 17, 1941, Serial No. 402,804

11 Claims. (Cl. 174—5)

This invention relates generally to protective guards and more specifically to protective guards adapted for use on poles and other structures which support overhead electrical conductors, for the purpose of protecting linemen working on the supporting structures from injury resulting from accidental contact with the supported energized conductors, the predominant object of the invention being to provide a protective guard of the type referred to above which is of such improved and unique construction and arrangement that it may be conveniently arranged in its effective position on a conductor support and when so positioned will protect linemen from the hazards produced by the proximity of highly energized electrical conductors.

As is well known to persons familiar with such matters, the duties of electric linemen frequently require them to climb poles and other conductor-supporting structures and work in close proximity to highly energized conductors supported by said supporting structures. Obviously, a lineman so occupied is in an extremely hazardous position because of the proximity of highly energized conductors with which his body may accidentally contact, and the prime purpose of the present invention is to provide means for effectively protecting a lineman from the dangers mentioned when he is occupied in the situation referred to.

Fig. 1 is a perspective of an assembly which includes the upper portion of a conductor supporting pole and a pair of the improved guard structures, one of said guard structures being shown in its extended, effective position, and the other being shown in the course of being arranged in its effective guarding position.

Fig. 2 is a fragmentary side elevation of the frame of one of the improved guard structures showing same in a collapsed condition.

Fig. 3 is a plan view of the frame and lift-pole of the improved guard structure.

Fig. 4 is a fragmentary front elevation of the upper portions of the frame and lift-pole of the improved guard structures, portions of the frame being shown in section.

Fig. 5 is a fragmentary front elevation of the frame of the guard structure illustrating the arrangement of the intermediate cross member of said frame.

Fig. 6 is a fragmentary horizontal section of the frame of the improved guard structure, illustrating in plan one of the means of the frame for supporting the guard structure in its effective position.

Fig. 7 is a side elevation of the structure illustrated in Fig. 6.

Fig. 8 is a fragmentary vertical section of the assembled guard structure, parts thereof being broken away because of limitations of drawing space.

In the drawings, wherein is shown for the purpose of illustration, merely, one embodiment of the invention, P designates in Fig. 1 of said drawings a pole with which are associated a plurality of crossarms C, said crossarms having mounted thereon suitable insulators S which support electrical conductors W¹, W², W³, W⁴, and W⁵, and W⁶. In the case of such an assembly of a pole, crossarms, and conductors as that illustrated in Fig. 1, articles of electrical equipment (not shown) are frequently mounted on the pole or on the crossarms between the opposed sets of conductors, and a lineman who is to do work in connection with the installation or maintenance of such equipment must climb to a position between said opposed sets of conductors. The purpose of the guard structure of the present invention is to afford such protection to a lineman working in the situation described that he may have complete freedom of movement of his arms and body without danger that he may accidentally come in contact with the energized conductors and thus be subjected to electrical shock.

In Fig. 1 of the drawings a pair of the improved guard structure, designated by the reference characters A and B, are shown in association with a pole and conductor assembly, but as these guard structures are duplicates in construction and use, the following detailed description will refer to a single guard structure, and the reference characters employed hereinafter will refer to corresponding parts of both of the guard structures illustrated in Fig. 1.

The improved guard structure includes a frame which is made up of a pair of opposed, vertical members 1 and 2, which preferably, though not necessarily, are in the form of poles formed from wood or other non-conducting material, each of said vertical members being in the form of a continuous element or an element made up of a plurality of sections suitably spliced together and detachable from each other for purposes of storage. The opposed vertical members 1 and 2 are spaced apart as shown in the drawings and said members are connected together by a plurality of cross members 3, 4, and 5, which are also formed of wood or other non-conducting material, the cross member 3 being

located at the upper ends of the vertical members 1 and 2, the cross member 5 being located at the lower ends of said vertical members, and the cross member 4 being located at a point intermediate of the upper and lower ends of said vertical members.

Each of the cross members 3, 4, and 5 is pivotally attached at its opposite ends to the vertical members 1 and 2, the manner of attaching the cross member 3 to the vertical members 1 and 2 being illustrated to the best advantage in Figs. 3 and 4. The means for pivotally attaching the cross member 3 at its opposite ends to the vertical members 1 and 2 comprises providing the opposite end portions of the cross member with slots 6 which are open at the ends of the cross member and at the top and bottom surfaces thereof. These slots receive eye portions 7 formed at the inner ends of bolts 8, the shank portions of which extend through openings formed through the vertical members 1 and 2, said bolts being secured to said vertical members by nuts 9. The means for pivotally attaching the opposite end portions of the cross member 3 to the vertical members 1 and 2 includes also pairs of plates 10, each of the vertical members 1 and 2 having a pair of plates 10 bolted, or otherwise secured thereto at opposite sides thereof and extended inwardly therefrom. The opposite end portions of the cross member 3 are disposed between the plates 10 of the vertical members 1 and 2 as shown to the best advantage in Fig. 3, and pivot pins 11 are extended through apertures formed through the plates 10 and through the portions of the cross member 3 located at opposite sides of the slots 6, said pivot pins 11 extending also through the eye portions of the bolts 8.

The cross members 4 and 5 are pivotally attached at their opposite ends to the vertical members 1 and 2 through the instrumentality of means constructed and arranged in accordance with the means just described for pivotally connecting the cross member 3 to said vertical members, and because of the similarity of said attaching means the attaching means of the cross members 4 and 5 need not be described in detail herein. The only difference between the attaching means of the cross members 3 and the corresponding attaching means of the cross members 4 and 5 is that the plates 10 of the attaching means of the two latter cross members are slightly longer and extend a greater distance inwardly of the locations of the pivot pins 11 as shown at 10' in Figs. 1 and 5.

Because of the pivotal attachment between the vertical members 1 and 2 and the cross members 3, 4 and 5 it is obvious that the frame produced by said vertical and cross members may be disposed in the rectangular arrangement in which said frame is shown in Fig. 1, or said frame may be collapsed by moving one vertical member downwardly and toward the other vertical member to bring the frame to the collapsed condition shown in Fig. 2. This pivotal arrangement for collapsing the members making up the frame of the guard structure is important in that it provides for greatly reducing the space required for storing the frame, for instance in a truck or other vehicle in which it is transported from place to place. The cross members 3 and 4 are provided at their approximate centers with portions 12 which are provided with annular grooves that serve a purpose to be hereinafter set forth.

5 Adjacent to the upper ends of the vertical members 1 and 2, each of said members has mounted thereon an arm 13 which extends from said member as shown in Fig. 1, and adjacent to the lower ends of said vertical members each thereof has mounted thereon a similar arm 14. Each of the arms 13 and 14 comprises a pair of spaced portions 15 which are disposed at opposite sides of the vertical member with which the arm is associated, and the arm is pivoted to the associated vertical member by a pivot pin 16 which passes through apertures formed through the spaced portions of the arm and through the associated vertical member. The spaced portions 15 of each arm 13 and 14 converge from the rear to the forward end of the arm, as shown in Fig. 6, and at the forward ends of said spaced portions an end member 17 is secured thereto. Also each arm includes a spacer 18 which is secured to and between the spaced portions 15 and extends beyond lower edges of the spaced portions (Fig. 7). Additionally each arm 13 and 14 includes an abutment 19 which is secured to and between the spaced portions 15 of the arm, said abutment serving to engage the associated vertical member when the arm has been moved to its horizontal position, as shown in Fig. 7, to arrest further upward movement of the outer end of the arm. The various parts which make up the arms 13 and 14 are formed from material which is a non-conductor of electricity, such, for instance, as wood, Bakelite, or other material possessing the desired characteristics.

35 Mounted at the outer end of each of the arms 13 and 14 is a clamp 20 which may be of any suitable construction and arrangement. The particular clamp illustrated in the drawings comprises a stationary clamp member 21 which is fixed to the end member 17 of the arm by a bolt 40 22, or otherwise, and is provided with a fixed jaw 23, and a movable jaw 24 that is adjusted toward and from the fixed jaw 23 by a screwthreaded operating element 25 which is in screwthreaded engagement with a portion 26 of the clamp member 21 and is provided with an eye at its lower end.

50 The frame of the improved guard structure disclosed herein which is made up of the vertical members 1 and 2, the cross members 3, 4, and 5, and the arms 13 and 14 is adapted to be elevated to the point of the conductor support at which the guard structure is to be used and applied to conductors supported by said conductor support. When the frame is being elevated as described 55 the arms 13 and 14 are extended from the vertical members in horizontal positions, said arms being retained in such positions by frictional engagement of portions of the spaced portions 15 of the arms with the vertical members 1 and 2. Also 60 at this time the movable jaws 24 of the clamps 20 are adjusted downwardly from the fixed jaws 23 of said clamps. The parts of the frame being properly arranged said frame is moved to a position where the fixed jaws 23 of the clamps 20 contact with and overlap the conductors to which the frame is to be attached, in Fig. 1 either the conductors W¹ and W³, or the conductors W⁴ and W⁶, and the clamps 20 are caused to mechanically grip the frame-supporting conductors by rotating 65 the operating elements 25 of the clamps with the aid of a suitable clamp stick, whose finger engages the eyes of said operating elements to adjust the movable jaws of the clamps to the conductor-gripping position. The frame of the 70 guard structure will, thereupon, be securely at- 75

tached to the conductors by which it is supported.

The improved guard structure includes also a lift-pole 27 which is formed from wood or other suitable non-conducting material and which is provided with hook element 28 that is fixed to and extends laterally from the lift-pole 27 as is shown to the best advantage in Fig. 8. The lift-pole 27 is assembled with the frame of the guard structure when the structure is in use by causing the outer hook-shaped end of the hook element 28 to be seated in the annular groove of the portion 12 of the cross member 3, as shown in Figs. 1 and 8, the lift-pole hanging vertically from such support. The lift-pole has mounted at its upper end a pulley 29 over which a rope 30 operates.

Forming a part of the guard structure is an extensible and collapsible wall 31 of the lazy tong type, said wall being composed of a plurality of strips of material pivoted together in the well known manner, and as is shown in Fig. 1 to permit said wall to be drawn to the extended position in which it is shown at the left-hand side of Fig. 1, or collapsed to the condition in which the wall 31 at the right-hand side of Fig. 1 is shown. The strips which make up the wall 31 may be formed from wood or any other suitable non-conducting material. A cross member 32 is provided at the upper end of the extensible and collapsible wall 31, and a similar cross member 33 is provided at the lower end of said wall 31. The cross members 32 and 33 are respectively secured to the wall 31 by links 34 and 35 (Figs. 1 and 8) which are pivotally attached to the cross members 32 and 33, in slots formed therein, by pivot pins 36, (Fig. 8), said links being also pivotally attached to the wall 31 by pivots which pivotally connect together certain of the strips of said wall. The cross members 32 and 33 are preferably formed of wood or other non-conducting material.

In the assembled condition of the guard structure the lower cross member 33 of the wall 31 is secured to the lift-pole 27 by a bolt 37 as is shown to the best advantage in Fig. 8. A portion of this bolt 37 is disposed in an opening formed through the cross member 33 and said bolt is secured to said cross member by nuts 38, and an extended portion of the bolt 37 passes through an opening formed through the lift-pole 27 and is secured thereto by a wing nut 39. The wall 31 has extended from parts thereof a plurality of bolts which are provided with eyes at their ends, one of said bolts being shown in Fig. 8 wherein it is designated by the reference character 40, and the eyes of the bolts referred to receive suitable rings 41 which embrace the lift-pole 27. Also one end portion of the rope 30 which operates over the pulley 29 at the upper end of the lift-pole is tied about the upper cross member of the wall 31 so that when the opposite end portion of the rope is pulled the wall 31 will be drawn from its collapsed position in which it is shown at the right-hand side of Fig. 1 to the extended position of said wall as shown at the left-hand side of Fig. 1. When the wall 31 is drawn to its extended position as shown at the left-hand side of Fig. 1 with the aid of the rope 30, the lower end portion of said rope is tied about the lift-pole 27, and the lower cross member 33 of said wall 31, as is also shown at the left-hand side of Fig. 1, to retain the wall in its upwardly extended position.

When the improved guard structure is to be erected in position for use at a pole or other con-

ductor support, the structure is removed from the truck or other vehicle in which it is transported from place to place in a collapsed condition. The frame, made up of the vertical members 1 and 2 and the cross members 3, 4 and 5, is adjusted to its expanded condition, the arms 13 and 14 are moved from their collapsed positions shown in Fig. 2 to their outwardly extended positions shown in Fig. 1 and the movable jaws of the clamps 20 are adjusted to their lowered positions. The frame is then elevated, with the aid of a block and tackle, for instance, to the point where the guard structure is to be employed, and said frame is secured to conductors with the aid of the clamps 20 as has already been explained herein. The lift-pole 27 is then elevated to the location of the frame and its hook element 28 is caused to engage the portion 12 of the cross member 3 so that said lift-pole hangs in a vertical position from said cross member 3. The extensible and collapsible wall 31 is then elevated to the location of the frame, the rings 41 moving into embracing relation with respect to the lift-pole 27, and the lower cross member of the wall 31 is secured to the lift-pole with the aid of the bolt 37 and wing nut 39. The rope 30, which is in position where it passes over the pulley 29 at the upper end of the lift-pole and where portions thereof hang downwardly from said pulley at opposite sides of the lift-pole, is tied at one of its ends to the upper cross member 32 of the wall 31. The opposite end portion of the rope 30 is then pulled to draw the upper portion of the wall 31 upwardly to its extended position as shown at the left-hand side of Fig. 1 and the end portion of the rope which is pulled is tied about the lower cross member 33 of the wall 31 and about the lift-pole to retain the wall in its upwardly extended position. During the upward movement of the wall 31 to its extended position the rings 41 slide longitudinally of the lift-pole 27 so as to guide the wall during such movement. Also the wall 31 is guided during its upward movement, and is held stable in its extended position, because of the fact that said wall is interposed between the vertical members 1 and 2 of the frame and the lift-pole 27 as is shown to the best advantage in Fig. 8.

When circumstances do not require that the wall 31 be extended to its full height, as shown at the left-hand side of Fig. 1, the hook element 28 of the lift-pole 27 may be caused to engage the portion 12 of the intermediate cross member 4 of the frame, in which event the wall 31 when drawn upwardly will be approximately one-half of the height of the fully extended wall when the lift-pole is suspended from the upper cross member 3 of the frame of the guard structure.

From the foregoing description it is obvious that when a pair of the improved guard structures are employed as shown in Fig. 1, a lineman working on the pole between the opposed guard structures is completely and effectively protected from injury as a result of coming in contact with the adjacent highly energized electrical conductors. Not only are the walls 31 interposed between the lineman and the conductors, but said walls are spaced inwardly considerable distances from the conductors by the arms 13 and 14.

I claim:

1. A guard structure comprising a frame, means for supporting said frame in its operative position, a guard wall supported by said frame and movable to extended and collapsed positions,

and means for moving said guard wall from its collapsed position to its extended position while said guard wall is supported by said frame, said guard wall moving means comprising a lift-pole supported by said frame, and means associated with said lift-pole for drawing said guard wall to its extended position.

2. A guard structure comprising a frame, means for supporting said frame in its operative position, a guard wall supported by said frame and movable to extended and collapsed positions, and means for moving said guard wall from its collapsed position to its extended position while said guard wall is supported by said frame, said guard wall moving means comprising a lift-pole supported by said frame, means for attaching the lower portion of said guard wall to said lift-pole, and means associated with said lift-pole for drawing said guard wall to its extended position.

3. A guard structure comprising a frame, means for supporting said frame in its operative position, a guard wall supported by said frame and movable to extended and collapsed positions, and means for moving said guard wall from its collapsed position to its extended position while said guard wall is supported by said frame, said guard wall moving means comprising a lift-pole supported by said frame, means for attaching the lower portion of said guard wall to said lift-pole, and a rope and pulley assembly associated with said lift-pole, said rope of said assembly being attached to the upper portion of said guard wall and being adapted to be operated to draw said guard wall upwardly to its extended position and to be tied to maintain the guard wall in its extended position.

4. A guard structure comprising a frame, means for supporting said frame in its operative position, a guard wall supported by said frame and movable to extended and collapsed positions, and means for moving said guard wall from its collapsed position to its extended position while said guard wall is supported by said frame, said guard wall moving means comprising a lift-pole supported by said frame, means for attaching the lower portion of said guard wall to said lift-pole, and a rope and pulley assembly associated with said lift-pole, said rope of said assembly being attached to the upper portion of said guard wall and being adapted to be operated to draw said guard wall upwardly to its extended position and to be tied to maintain the guard wall in its extended position, said frame and said lift-pole being disposed at opposite sides of said guard wall and immediately adjacent same so as to guide the guard wall during upward movement thereof.

5. A guard structure comprising a frame, means for supporting said frame in its operative position, a guard wall supported by said frame and movable to extended and collapsed positions, and means for moving said guard wall from its collapsed position to its extended position while said guard wall is supported by said frame, said guard wall moving means comprising a lift-pole supported by said frame, means for attaching the lower portion of said guard wall to said lift-pole, said rope of said assembly being attached to the upper portion of said guard wall and being adapted to be operated to draw said guard wall upwardly to its extended position and to be tied to maintain the guard wall in its extended position, said frame and said lift-pole

being disposed at opposite sides of said guard wall and immediately adjacent same so as to guide the guard wall during upward movement thereof, and elements supported by said guard wall which embrace said lift-pole and move longitudinally thereof during upward movement of the guard wall to assist in guiding the movement of said guard wall.

6. A guard structure adapted for use at the location of electrical conductors comprising a frame, means for supporting said frame in its operative position, said frame supporting means comprising arms extended from said frame and provided with clamps adapted to engage adjacent electrical conductors so as to support said frame from said electrical conductors, a guard wall supported by said frame and movable to extended and collapsed positions, and means for moving said guard wall from its collapsed position to its extended position while said guard wall is supported by said frame.

7. A guard structure adapted for use at the location of electrical conductors comprising a frame, means for supporting said frame in its operative position, said frame supporting means comprising arms pivoted to and extended from said frame and provided with clamps adapted to engage adjacent electrical conductors so as to support said frame from said electrical conductors, a guard wall supported by said frame and movable to extended and collapsed positions, and means for moving said guard wall from its collapsed position to its extended position while said guard wall is supported by said frame.

8. A guard structure adapted for use at the location of electrical conductors comprising a frame, means for supporting said frame in its operative position, said frame supporting means comprising upper and lower pairs of arms pivoted to and extended from said frame and provided with clamps adapted to engage adjacent electrical conductors so as to support said frame from said electrical conductors, a guard wall supported by said frame and movable to extended and collapsed positions, and means for moving said guard wall from its collapsed position to its extended position while said guard wall is supported by said frame.

9. A guard structure adapted for use at the location of electrical conductors comprising a frame composed of opposed side members and cross members, said cross members being pivotally attached to said side members to provide for collapsing the frame, means for supporting said frame in its operative position, said frame supporting means comprising arms pivoted to and extended from said opposed side members of the frame and provided with clamps adapted to engage adjacent electrical conductors so as to support said frame from said electrical conductors, a guard wall supported by said frame and movable to extended and collapsed positions, and means for moving said guard wall from its collapsed position to its extended position while said guard wall is supported by said frame.

10. A guard structure comprising a frame composed of opposed side members and cross members, said cross members being pivotally attached to said side members to provide for collapsing the frame, means for supporting said frame in its operative position, a guard wall supported by said frame and movable to extended and collapsed positions, and means for moving said guard wall from its collapsed position to its extended position while said guard wall is sup-

ported by said frame, said guard wall moving means comprising a lift-pole supported by said frame, means for attaching the lower portion of said guard wall to said lift-pole, and a rope and pulley assembly associated with said lift-pole, said rope of said assembly being attached to the upper portion of said guard wall and being adapted to be operated to draw said guard wall upwardly to its extended position and to be tied to maintain the guard wall in its extended position.

11. A guard structure adapted for use at the location of electrical conductors comprising a frame composed of opposed side members and cross members, said cross members being pivotally attached to said side members to provide for collapsing the frame, means for supporting said frame in its operative position, said frame supporting means comprising arms pivoted to and extended from said side members of said

frame and provided with clamps adapted to engage adjacent electrical conductors so as to support said frame from said electrical conductors, a guard wall supported by said frame and movable to extended and collapsed positions, and means for moving said guard wall from its collapsed position to its extended position while said guard wall is supported by said frame, said guard wall moving means comprising a lift-pole supported by said frame, means for attaching the lower portion of said guard wall to said lift-pole, and a rope and pulley assembly associated with said lift-pole, said rope of said assembly being attached to the upper portion of said guard wall and being adapted to be operated to draw said guard wall upwardly to its extended position and to be tied to maintain the guard wall in its extended position.

MERLE L. FISHER.
